APPARATUS FOR THE MANUFACTURE OF
INDENTED CORRUGATED PAPER PROD-
UCTSCharles Quincy Ives, Reading, Mass., assignor to
Sherman Paper Products Corporation, New-
ton, Mass., a corporation of Massachusetts

Application November 9, 1937, Serial No. 173,629

2 Claims. (CL. 154—30)

This invention relates to apparatus for the manufacture of a single-faced corrugated paper product whose corrugations are indented or broken down along lines intersecting the corrugations, preferably along closely spaced criss-crossing lines intersecting the corrugations at a substantial angle, for instance, an angle of about 45°. Such a single-faced corrugated paper product is disclosed in my United States Reissue 5 Patent No. 20,034, dated July 14, 1936, as being of value for wrapping purposes, since it flexes readily at all angles across the corrugations as well as along lines parallel to the corrugations and can thus be made to assume satisfactorily 10 the external configuration of the body or package being wrapped, especially at corners or edges, with the corrugations affording essentially the same cushioning or protective effect on the wrapped body or package as when the corrugations are not locally indented.

In producing flexible, single-faced corrugated paper products of the foregoing type, I have observed that it is sometimes difficult to indent permanently to the desired sharpness or depth 25 the corrugations of certain grades of corrugated paper. This difficulty arises particularly in the case of relatively hard or "snappy" corrugated papers, such as corrugated kraft paper, glassine paper, parchment paper, etc., whose corrugations 30 are so resilient that they tend to recover or spring back to a pronounced undesirable degree at their locally indented regions after the indenting pressure has been removed therefrom.

The apparatus of the present invention is 35 adapted for the manufacture of a single-faced corrugated paper sheet that is indented locally along lines intersecting the corrugations while the localities being indented are simultaneously treated or wetted with a fiber-softening or plasticizing agent enabling the retention permanently of the indentures in the corrugations substantially as originally created or impressed. It thus becomes possible to produce single-faced corrugated paper products of appropriate flexibility 40 across the corrugations even when the corrugations of the corrugated paper ply are of comparatively high resiliency and recovery after local indentation in the absence of a fiber-softening or plasticizing agent. While it is possible by the 45 apparatus hereof to treat or wet the corrugated localities being indented in the course of the indenting operation with various fiber-softening or plasticizing agents, such as glycerine, oil, etc., yet water or aqueous compositions have been 50 found to be quite satisfactory and least expen-

sive for this purpose. It is evidently the case that water softens or plasticizes paper sufficiently to enable the fibers in the corrugated localities being indented to rearrange themselves permanently to the indented or broken-down configuration imparted to the corrugations at the time of their indentation or local break-down. Because indentation or local break-down of the corrugations and the fiber rearrangement incident thereto weakens the corrugated paper ply 10 at its indented localities, it is distinctly preferable to use as the softening or plasticizing medium for such localities an aqueous composition containing a suitable binder that strengthens or bonds together the fibers at the regions of indentation or break-down of the corrugations. Various aqueous binder compositions, including aqueous solutions or suspensions of starch, glue, sodium silicate, gums, etc. may serve as fiber-softening agents for the purposes hereof, but it 15 is preferable to employ aqueous compositions containing flexible binders, such as, rubber latex, artificial aqueous rubber dispersions, aqueous asphalt emulsions, aqueous emulsions of nitro-cellulose, aqueous cellulose xanthate solutions, or 20 the like. These binders thus set or dry out in the indented regions of the corrugations to strengthen or toughen such regions against tearing or rupture while avoiding undesirable stiffening of such regions.

The indentation of the corrugations of the corrugated paper ply along closely spaced lines intersecting the corrugations is readily and continuously effected by providing in the apparatus hereof rolls whose peripheries present indenting elements in the form of ribs or knives. The application of the fiber-softening or plasticizing agent to the corrugations at their localities being indented can be effected economically in the course of the indenting operation by depositing 35 a film of such agent continuously on the edges of such ribs or knives immediately before they pass into indenting or pressure contact with the corrugated paper ply. Thus, the liquid plasticizing agent may be transferred conveniently in 40 film form by a suitable transfer roll to the edges of the indenting knives or ribs from the periphery of a roll rotating partially submerged in a bath of such plasticizing agent. If desired, the plasticizing agent may be dyed or pigmented so 45 that when transferred or deposited in the indentures or recesses of the indented corrugations, colored lines of attractive or ornamental appearance are developed in the finished flexible corrugated paper product hereof.

With the foregoing and other features and objects in view, the present invention will now be described in further detail with particular reference to the accompanying drawings, wherein—
5 Figure 1 shows in side elevation more or less diagrammatically and conventionally an apparatus embodying the present invention.

Figure 2 is a plan view of the two indenting rolls forming part of the apparatus.

10 Figure 3 depicts in fragmentary perspective an indenting roll.

Figure 4 is a plan view of a fragment of the indented or flexible corrugated paper product.

15 Figure 5 shows in greatly enlarged perspective view a fragment of the indented or flexible corrugated paper product.

Since the single-faced corrugated paper sheet may be produced as customarily by progressively corrugating a continuous paper sheet and then 20 adhesively and progressively securing the corrugated sheet at the crests or apices of its corrugations to a continuous flat or plane paper sheet, it is unnecessary to illustrate the machine elements for producing such single-faced corrugated paper sheet. Accordingly, Figure 1 shows the prefabricated single-faced corrugated sheet S consisting of the corrugated paper ply 10 and the flat paper facing ply 11 as it is being 25 progressively or continuously delivered from the

30 corrugating and facing machine with its facing ply adhesively bonded to the corrugated ply where the crests 12 of the corrugations make contact with the facing ply. The single-faced corrugated sheet S is preferably subjected to a 35 two-stage indenting treatment, namely, a first-stage indenting treatment between a pair of rolls 13 and 14 and a second-stage indenting treatment between rolls 15 and 16. The upper rolls 13 and 15 of the two pairs of rolls are the indenting rolls and the lower rolls 14 and 16 are the base or backing rolls on which the sheet S is supported as the corrugated paper ply is being 40 indented. The periphery of the indenting roll 13 presents multiple spiral ribs or threads 17 which, as best appears in Figure 5, are of substantially triangular cross-section and extend as 45 continuous helical elements from one end of the roll to the other. While the ribs 17 may occur at various angularities to the corrugations of the corrugated paper ply, it is preferable that the angularity be substantially 45° so that the 50 indentures created in the corrugations of the corrugated paper ply will run along lines intersecting the corrugations at substantially 45°. The ribs 17 may be formed on a steel roll periphery by machining the roll on a lathe equipped with a cutting tool-carrier whose milling or cutting tool undergoes rotation as well as longitudinal 55 traverse of the roll. The desired angularity of the helical ribs or threads 17 may thus be determined by the rate of rotation and longitudinal travel of the cutting tool relative to the roll. The number of multiple ribs or threads 17 thus cut in the roll periphery may vary, depending 60 upon its diameter and the spacing of indentures to be created in the corrugated paper ply. It is, however, desirable that the successive or multiple spiral ribs 17 be spaced apart so that the lines of indenture created thereby in the corrugated paper ply are spaced about $\frac{1}{8}$ " to $\frac{3}{8}$ " from one another. The indenting roll 15 has a ribbed peripheral configuration essentially similar to that of the roll 13, excepting that its multiple helical ribs or threads are arranged substantially 65 perpendicularly to the threads of the

roll 13. In passing under the successive indenting rolls, the corrugations of the corrugated paper ply are thus indented along closely spaced criss-crossing lines 18 intersecting the corrugations at angles of substantially 45°.

In order to maintain the indentures in the corrugations of the desired depth, as originally impressed, after the corrugated sheet has emerged from under the indenting rolls 13 and 15, the fiber-softening or plasticizing agent may be progressively deposited on the edges of the ribs 17 immediately before they contact with and indent the corrugations of the corrugated paper ply. To this end, such agent may be transferred in liquid film form to the edges of the ribs 17 from a transfer roll 19 making wiping contact with the periphery of a roll 20 rotating partially submerged in a bath 21 of such agent. By regulating the speed of rotation of the roll 20 in the bath 21 of such agent, it is possible to control the thickness of the liquid film or amount of agent picked up by the periphery of the roll 20 and thence transferred by the periphery of the transfer roll 19 to the edges of the ribs 17. Each of the rolls 13 and 15 are shown equipped with similar instrumentalities for depositing progressively a film of the fiber-softening or plasticizing agent to all of the edges of the ribs 17.

As already indicated, the fiber-softening or plasticizing agent may advantageously be an aqueous binder composition, for instance, rubber latex, which may be dyed or pigmented to any desired color. Indeed, the agent for the roll 13 may be of a different color than that for the roll 15 so as to impress or print criss-crossing lines of different colors for pleasing ornamental effect in the indentures created in the corrugations of the corrugated paper ply. As appears best in Figure 5, the softening agent, although applied by the edges of the ribs 17 essentially only at the bases of the regions of indenture, may diffuse or migrate more or less upwardly over the inclined walls of the indentures. The fibers of the paper are thus softened or plasticized precisely in those regions where the paper corrugations undergo maximum indenture; and such softening or plasticizing action on the fibers practically inhibits tendency for the indented regions of the paper corrugations to recover or reassume to any significant extent their original corrugated form. The plasticization and permanent rearrangement of the paper fibers or paper portions constituting the regions of indentation of the corrugations is accompanied by some weakening of the paper at such regions of indentation, but this weakening effect may be more than offset by the bonding together of the rearranged fibers with the rubber or other binder left as a dried residue at such regions, as indicated at 22, from the fiber-softening or plasticizing composition. The finished or indented corrugated paper product is thus without tendency to tear on the regions or lines of indentation 18, which regions may, in fact, be of distinctly greater toughness and tear-resistance than the rest of the product.

The water of the fiber-softening medium applied locally to the regions of indenture of the corrugation of the corrugated paper ply may be allowed to evaporate naturally therefrom, although such evaporation may be hastened by passing the indented corrugated paper sheet S as it comes from under the indenting roll 15 over a hot drier drum 23 on its way to a rewinding reel 24. Should the medium contain dispersed rubber, asphalt, and/or pigment dyes, or similar

agents, the evaporation of the water sets or dries such agents. In some instances, the sheet S may be dried after the indentation and localized wetting of its corrugated paper ply, as by passage 5 through a hot air chamber, and cut into individual sheets of predetermined size for packaging and sale.

So far as concerns the plane or flat paper facing of the flexible corrugated paper product here- 10 of, it is possible to use in lieu thereof flexible facing fabrics, such as cheesecloth, linen, etc. It is also possible to use in lieu thereof papers of a crinkled or creped nature either alone or reinforced by fabric. Accordingly, in charac- 15 terizing the indented or flexible corrugated paper product as a single-faced corrugated paper sheet, it is to be understood that the flat facing sheet may be paper or such equivalents of paper as I have just indicated. In respect of the indenting 20 rolls 13 and 15, whose peripheries present multiple helical ribs or threads as the indenting elements, it might be noted that in actual practice the use of fifteen threads per foot in an indenting roll of approximately 6" diameter with a spacing of 25 about $\frac{1}{4}$ " between the rib apices leads to indented or flexibilized single-faced corrugated paper products eminently satisfactory as a wrapping material. It will be appreciated that the peripheries of both indenting rolls are similarly 30 configured, excepting that the threads or ribs in one roll extend practically perpendicularly to the threads or ribs in the other roll and that both indenting rolls as well as their base rolls 14 and 16 are positively driven or rotated at a speed 35 coordinated preferably exactly with the speed at which the single-faced corrugated paper is being delivered thereto.

I claim:

1. In a machine for locally indenting the cor- 40 rugations of the corrugated paper ply of a single-faced corrugated paper sheet and thereby render- ing said sheet readily flexible across its corruga-

tions, a pair of coacting rolls through whose nip said sheet may be passed, said pair of rolls including an indenting roll whose periphery presents multiple closely spaced helical ribs by which the corrugations of said corrugated paper ply 5 may be indented along lines intersecting said corrugations at an angle, and a second pair of coacting rolls through whose nip said sheet may be passed from said first pair of rolls, said second pair of rolls including an indenting roll whose 10 periphery also presents closely spaced helical ribs by which the corrugations of said corrugated paper ply may be indented along lines intersecting said corrugations but criss-crossing the lines of indentation created in the corrugations by the 15 ribs of said first-named indenting roll.

2. In a machine for locally indenting the corrugations of the corrugated paper ply of a single-faced corrugated paper sheet and thereby rendering said sheet readily flexible across its corrugations, a pair of coacting rolls through whose nip said sheet may be passed, said pair of rolls including an indenting roll whose periphery presents multiple closely spaced helical ribs by which the corrugations of said corrugated paper ply 20 25 may be indented along lines intersecting said corrugations at an angle, a second pair of coacting rolls through whose nip said sheet may be passed from said first pair of rolls, said second pair of rolls including an indenting roll whose periphery 30 35 also presents closely spaced helical ribs by which the corrugations of said corrugated paper ply may be indented along lines intersecting said corrugations but criss-crossing the lines of indentation created in the corrugations by the ribs of said first-named indenting roll, and means for progressively depositing a film of liquid on the edges of the ribs of each said indenting rolls before they make contact with said corrugated paper ply. 40

CHARLES QUINCY IVES.
